I claim the ornamental design for a corner protector, as shown and described.

DESCRIPTION

FIG. 1 is a perspective view of a corner protector, showing my design;

FIG. 2 is a bottom view of the corner protector of FIG. 1;

FIG. 3 is a top view of the corner protector of FIG. 1;

FIG. 4 is a front elevation of the corner protector of FIG. 1;

FIG. 5 is a rear elevation of the corner protector of FIG. 1;

FIG. 6 is a left elevation of the corner protector of FIG. 1; and,

FIG. 7 is a right elevation of the corner protector of FIG. 1.
